HIP MOUNTED QUIVER

Jack Stanley Howard, Pasadena, Calif.

Application June 21, 1954, Serial No. 31,084

Term of patent 14 years

(Cl. D30—1)

Fig. 1 is a front elevation of a hip mounted quiver showing my new design,

Fig. 2 is a rear elevation,

Fig. 3 is a side elevation as viewed from the right hand side of Fig. 1,

Fig. 4 is a top plan view,

Fig. 5 is a bottom plan view, and

Fig. 6 is a transverse sectional view taken on the line 6-6 of Fig. 1.

I claim:

The ornamental design for a hip mounted quiver, substantially as shown.
